DESIGN FOR A COMBINED BOTTLE DISPLAY AND HOLDER THEREFOR

Eugene J. Korda, New York, N. Y., assignor to
Dermetics, Inc., New York, N. Y., a corpora-
tion of Washington

Application February 6, 1940, Serial No. 90,070

Term of patent 7 years

To whom it may concern:

Be it known that I, Eugene J. Korda, a citizen of the United States, residing at New York, city, county, and State of New York, have invented a new, original, and ornamental Design for a Combined Bottle Display and Holder Therefor, of which the following is a specification, reference being had to the accompanying drawing, forming part thereof, wherein:

Figure 1 is a perspective view of the combined bottle display and holder therefor, showing my new design;

Fig. 2 is a top plan view of the combined bottle display and holder therefor of Fig. 1 with the bottles removed; and

Fig. 3 is a perspective view with the lid and base of the combined bottle display and holder therefor separated from each other.

I claim:

The ornamental design for a combined bottle display and holder therefor, substantially as shown.

EUGENE J. KORDA.
